GEORGE B. MOORE AND AUSTIN J. PRATT, OF SPRINGFIELD, MASSACHUSETTS.

BALL-COCK.

1,140,054.

Specification of Letters Patent.

Patented May 18, 1915.

Application filed May 13, 1913. Serial No. 767,377.

To all whom it may concern:

Be it known that we, GEORGE B. MOORE and AUSTIN J. PRATT, both citizens of the United States of America, and residents of 5 Springfield, in the county of Hampden and State of Massachusetts, have invented certain new and useful Improvements in Ball-Cocks, of which the following is a full, clear, and exact description.

10 This invention relates to ball cocks or valves such, for instance, as the kind illustrated and described in Letters Patent of the United States issued May 14, 1901, No. 674,276, to G. B. Moore, herein named.

15 Ball cocks, as well known, are in many cases employed in water closet tanks in which when the tank valve is opened the discharge of the water from the tank through the pipe to the water closet bowl is insured 20 by siphonic action. The outdrawing of the water from the tank, as usual, causes the lowering of the ball float which controls the ball cock so that the latter is opened for the inflow of water into and for the refilling 25 of the tank; and in many cases the inflow of the water through the ball cock into the tank is sufficient to maintain the water level in the tank at a sufficient height to preserve the conditions for the siphonic action so 30 that water will for an indefinite period flow into and out from the tank resulting in great waste as well as the annoyance caused by too long running of the water.

One object of this invention is to provide 35 means in the ball cock so that after the tank valve shall have been opened and the water level lowered whereby, as usual, the ball cock will be opened for the fresh supply of water into the tank, the passage of 40 the water through the ball cock into the tank will be then very much restricted so that for a time after the full opening of the ball cock it will be almost closed with the result that on account of the small amount 45 of water entering the tank, the water level will be, with certainty, lowered to the extent of breaking the siphon, under which conditions the tank valve will close to be followed by the maximum flow of the water 50 through the ball cock and the gradual lessening of the flow until the tank is refilled, whereupon, as usual, the ball cock will be closed and the flow terminated.

A further object of the invention is to

provide means in the ball cock whereby, 55 when desired, the movement of the valve stem for opening may be limited so that the inflow of the water through the ball cock cannot be restricted, thus rendering the ball cock available as a simple ball cock and for 60 use in tanks other than those having a siphon discharge.

The invention is described in conjunction with the accompanying drawings and is set forth in the claims.

In the drawings:—Figure 1 is a central longitudinal sectional view through the ball cock, the valve proper thereof being shown as in its fully opened position and the restricting member as in its closing relation to 70 the water passage through the cock. Fig. 2 is a view similar to Fig. 1 but showing the adjustable member so positioned as to render the restricting member incapable of assuming its position for a restriction of the 75 flow of water through the cock.

The body of the ball cock is constituted by the two sections 1 and 2,—the section 1 having at its end a neck *a* which has a close fit into the cylindrical opening in the section 2.

The two sections have external flanges which are engaged by a constrictive yoke *b* for holding the sections together with the interposed packing substantially as set forth 80 in the aforementioned patent.

The sectionally formed casing has a chamber *d* therein with which the water inlet passage *f* is in communication; and the casing also has the chamber *g* therein from which 90 the water delivery passage *h* leads.

Between the chambers *d* and *g* is a connecting passage *i* the diameter of which is less than that of either of the said chambers and the ends of the wall of such passage 95 surrounding the mouth thereof form valve seats *j* and *k*.

The provision of such passage with the valve seats at the ends thereof is made, in the present instance, by an annular bushing 100 *m* which is fitted and secured in the casing section 1 and has the end thereof projected more or less into the chamber *d* which is surrounded by the casing section 2.

o represents the valve stem which is arranged longitudinally within the valve casing, one end thereof projecting outwardly beyond the end of the casing through the

annular nut p and packing p^2 and is engaged by an arm q of an angular lever to the other arm q^2 of which the rod which carries the ball float may be adjustably secured,—the 5 said lever arm q being by link q^3 which is pivoted thereto, pivotally connected at q^4 to an upstanding lug at the top of the valve casing all substantially as shown in the aforementioned patent.

10 The portion of the valve stem which is between the chamber b and g is of a diameter considerably less than that of the opening i which connects such chambers; and s represents the valve proper of the ball cock 15 carried by the valve stem and having its location at the inlet end of the passage i , and coacting with the valve seat opening j at such end, it being understood that when the tank is full and the ball float consequently elevated, the valve s will be seated 20 and operable to close any flow of water from the inlet chamber d through the passage i for delivery into the tank.

t is a member carried by, and preferably 25 formed as a part of the valve stem within the chamber g and properly positioned for coaction with the mouth of the passage i at the outlet end thereof.

This member t is shown as of substantially frusto-conical form, and under the 30 maximum range of operation of the float-carrying and valve-stem-operating lever is brought, when the valve s is moved to its most widely opened position relatively to the valve seat j , into proximate relation to the mouth end k of the passage i , for greatly 35 restricting the flow or passage of water from the inlet chamber to the delivery passage of the valve.

40 It will be stated that the seating portion of the valve s , in practice, is composed of rubber,—or in any event the valve proper, s , is so constructed for its coöperation with the valve seat j that when the valve proper 45 is closed the flow of water through the cock will be entirely prevented; but it is to be especially understood that the valve like member t , by its nature, form or construction, is to be of such character that some 50 water, when the valve proper is opened, may be forced through the passage i for delivery through the ball cock. The most simple, inexpensive and satisfactory practice is to leave the frusto-conical member t , which is 55 produced as a part of the valve stem by casting in brass, unfinished, that is left rough with the indentations or sand pits remaining therein, for when this part is so made and even when forced with considerable 60 pressure aganist the mouth end at the outlet of the passage i , a considerable, though proportionately much reduced quantity of water may pass through the cock. Now assuming this ball cock is used in a water- 65 closet tank in which in conjunction with

the tank valve a siphon outlet pipe is employed, it will be understood that on the opening of the tank valve the water will be exhausted from the tank by siphonic action which will continue until the water has 70 become exhausted from the tank to such an extent as to cause the breaking of the siphon whereby the flow of water from the tank is expected to stop. Now when the water is very much lower in the tank so as to widely 75 open the valve s of the ball cock, but before the water has become lowered sufficiently to cause a breaking of the siphon, the inflow of water into the tank through the ball cock would, under many conditions, 80 be sufficient for the maintenance of the water at a sufficient height to preserve the siphon and result in a continued inflow and outflow of water indefinitely; but by the restriction for a period after the valve proper 85 has been fully opened, by the bringing of the valve-like member t to its partially closing relation to the adjacent mouth of the passage i , the inflow of the water is temporarily much checked, so that the siphon may 90 assuredly be broken; then after the closing of the tank valve the water rising in the tank as permitted by what may in a sense be regarded as a copious leakage past the restricting member t , will with sufficient 95 promptness cause such an endwise movement of the valve stem as to carry the member t free and clear from the valve seat opening k so that the ball cock becomes operative, 100 in the manner of ordinary ball cocks, to secure rapid inflow into the tank to result in the final closing of the cock.

As these ball cocks are to be made up in stock for distribution for employment in water-closet tanks, in which gravity, or slow 105 closing, tank valves are used which are of a character distinguished from any operating in conjunction with a siphonage pipe, it becomes desirable to provide adjustable means whereby in such cases the ball cock 110 may be employed without the capability of the valve-like member t ever attaining its water restricting relation to the mouth end of the passage i ; and to this end the stop screw u is provided as an adjustable appurtenance to the valve stem operating means. As shown the shank of this stop screw u is 115 screw engaged in a tapped hole therefor which is formed near the elbow of the angular lever q , q^2 . When the cock is to be 120 used as represented in Fig. 1 to secure the period of water restriction, as heretofore fully described, this stop screw is positioned closely in relation to the edge of the lever so that the latter may have a maximum of 125 swinging movement; but by positioning the screw in an extended relation, as shown in Fig. 2, the valve stem while capable of all sufficient endwise movement for amply opening the valve proper, s , nevertheless, may 130

not have such a degree of movement as to bring the member *t* to a choking or obstructing relation to the mouth *h* of the passage *i* which connects the discharge and inlet chambers of the cock.

5 The body of the main valve is of cylindrical form and has a close fit in a cylindrical casing *u*² which by being closed forms a vacuum chamber serving in the action of the valve to prevent water hammering.

10 We claim:—

1. A ball cock comprising in combination with a casing having a pair of chambers, one having a water inlet and the other a 15 discharge outlet, and a passage formed with valve seats at opposite ends connecting said chambers, of a valve stem having a portion of less diameter than and extending through, the connecting passage; a valve 20 on said rod adjacent the inlet valve-seat end of the connecting passage and coacting therewith; a member on the valve rod at the opposite end of said passage adapted on the opening of the valve to have an approximately 25 closed relation to said opposite end of the passage to restrict the inflow of water, substantially as and for the purpose specified.

2. A ball cock comprising in combination 30 with a casing having a pair of chambers, one having a water inlet and the other a discharge outlet, and a bushing formed with valve seats at opposite ends connecting said chambers, of a valve stem having a portion 35 of less diameter than the internal diameter of and extending through the bushing; a valve on said rod adjacent the inlet valve-seat end of the bushing and coacting therewith; a valve member on the valve rod at 40 the opposite end of said bushing adapted on the opening of the valve to have an approximately closed relation to said opposite end of the bushing to temporarily restrict the inflow of the water; means connected to 45 the valve stem externally of the casing to impart endwise movement to the valve stem, and adjustable means carried by the valve stem moving means to limit the movement of the valve stem in the opening direction.

50 3. A ball cock comprising in combination with a casing having a pair of chambers, one having a water inlet and the other a discharge outlet, and a bushing formed with valve seats at opposite ends connecting 55 said chambers, of a valve stem having a portion of less diameter than the internal diameter of and extending through the bushing; a valve on said rod adjacent the inlet valve seat end of the bushing and co- 60 acting therewith; a valve member on the valve rod at the opposite end of said bushing adapted on the opening of the valve to have an approximately closed relation to said opposite end of the bushing to temporarily 65 restrict the inflow of the water; a

lever pivotally connected to the valve stem externally of the casing and having a link connection with the casing; and a set screw carried by the lever adapted to abut against the casing and coöperate therewith under 70 proper adjustment thereof to limit the movement of the valve stem in the opening direction.

4. A ball cock comprising in combination with a casing having a pair of chambers, one having a water inlet and the other chamber a discharge outlet, and a bushing in the casing formed with valve seats at opposite ends connecting said chambers, of a cylindrical member in the chamber having 80 the water inlet with an open end toward said bushing and closed at its other end; a valve stem having a portion of less diameter than the internal diameter of and extending through the bushing; a valve on 85 said rod adjacent the inlet valve-seat end of the bushing and co-acting therewith and having a portion to slidably engage in the cylindrical member; a valve member on the valve rod at the opposite end of said bushing 90 adapted on the opening of the valve to have an approximately closed relation to said opposite end of the bushing to temporarily restrict the inflow of water, a portion on the valve rod beyond said valve 95 member having a sliding fit in the valve casing; and means connected to the valve stem externally of the casing to impart endwise sliding movement to the valve stem.

5. In a ball cock, the combination with 100 a casing having an inlet, and a water way therethrough connecting with said inlet, said water way being formed with a main valve seat and with a supplemental seat in axial alinement with such main seat, of a 105 valve stem extending within and along the water way and through said valve seats, and of smaller diameter than the openings thereof, and having a valve for positively closing at the main valve seat, and having 110 a valve member for coaction with and to approximately close at the supplemental seat, when the main valve is moved to the maximum of its opening relation to temporarily restrict the inflow of the water, and 115 means externally of the casing for endwise moving the valve stem.

6. In a ball cock, the combination with 120 a casing having a chamber therein with which a water inlet passage connects, and having another chamber from which a water delivery passage leads, and an annular bushing piece secured in the casing between said chambers and forming the passage to connect such chambers, the mouths 125 at the opposite ends of which passage forming valve seats, of a valve stem having a portion thereof smaller in diameter than the passage through said annular bushing and extending through the same, the valve 130

stem having a valve at the inlet end of said passage coacting with the adjacent seat, and having a valve member at the opposite end of said passage adapted on movement in the 5 opening direction of the valve member to engage its seat, said latter valve and valve seat being relatively unsymmetrical whereby upon seating of the valve the inflow of water will be temporarily restricted and 10 only a small portion of water can pass, and

means externally of the casing for endwise movement of the valve stem.
